DOOR LATCH STRUCTURE

George Janonis, Detroit, Mich.

Application April 2, 1951, Serial No. 218,825

5 Claims. (Cl. 292—216)

1

This invention relates generally to latch assemblies and refers more particularly to improvements in latch mechanisms of the pivoted or rotary bolt type.

It is one of the objects of this invention to provide a latch mechanism having a rotary bolt and having means for releasing the bolt from its latched position in response to movement of a control in the direction of opening movement of the closure member in connection with which the latch is associated.

It is another object of this invention to provide a latch mechanism having manually operable controls at opposite sides of the closure movable in the general direction of opening movement of the closure to release the bolt from its latched position. With a construction of the above type, it is possible to provide an inside control in the form of a push button arranged flush or substantially flush with the inner panel of the closure. This feature is desirable especially in vehicle body doors, since it renders it possible to omit the usual door handles at the inner sides of the doors, and thereby not only improves the appearance of the interior of the body, but in addition, simplifies releasing of the latch from the interior of the vehicle.

It is still another object of this invention to provide latch mechanism of the above type having means for locking the bolt in its latched position and having controls accessible for manipulation from either side of the closure for operating the locking means.

It is a further object of this invention to provide latch mechanism embodying the above features and composed of a relatively few simple parts capable of being inexpensively manufactured and installed.

It is a still further object of this invention to provide a keeper for the rotary bolt constructed to serve as a dovetail member.

The foregoing as well as other objects will be made more apparent as this description proceeds, especially when considered in connection with the accompanying drawings, wherein:

Figure 1 is a diagrammatic side elevational view of a part of a vehicle body having a door with latch mechanism constructed in accordance with this invention;

Figure 2 is a sectional view taken on the line 2—2 of Figure 1;

Figure 3 is a sectional view taken on the line 3—3 of Figure 1;

Figure 4 is a sectional view taken on the line 4—4 of Figure 2;

2

Figure 5 is a sectional view taken on the line 5—5 of Figure 2;

Figure 6 is a sectional view taken on the line 6—6 of Figure 5;

Figure 7 is a sectional view taken on the line 7—7 of Figure 2;

Figures 8 and 9 are respectively perspective views of parts of the outside control for the latch; and

10 Figure 10 is a sectional view taken on the line 10—10 of Figure 4.

It will be understood as this description proceeds that many of the features of the latch mechanism forming the subject matter of the

15 present invention may be incorporated in latches for various different types of closures. For example the latch mechanism to be presently described may be advantageously used with slight variations in connection with vehicle hoods or 20 rear deck lids. However the invention finds particular utility when employed in association with vehicle body doors, and is shown herein as applied to a typical body door 10.

Briefly the door 10 comprises an outer panel 25 11, an inner panel 12 spaced laterally from the outer panel and connected to the peripheral edge of the latter by a flange 13 formed integral with the inner panel 12. In the present instance the door 10 is hinged at its front edge 14 (Figure 1), 30 and the rear or swinging edge assumes a position adjacent a conventional body pillar 15 in the closed position of the door.

The door is held in its closed position by latch mechanism designated generally by the numeral

35 16 in the several figures of the drawings. The latch mechanism 16 has a supporting plate or bracket 17 which is secured to the rear edge flange 13 of the door, and is housed in the space 18 between the inner and outer door panels. As

40 shown in Figure 5 of the drawings, the central portion of the bracket 17 is bent laterally forwardly to provide a channel 19 which is open rearwardly of the door and registers with a slot 20 formed in the rear edge flange 13 of the door.

45 Referring now to Figures 4 and 5, it will be noted that a bolt 21 of the rotary type is supported in the channel 19 of the bracket 17 for pivotal movement about a vertical pin 22. The pin 22 extends vertically through aligned openings in the flanges of the channel 19, and is secured in place in any suitable manner.

The bolt 21 is shown in Figure 4 of the drawings in two positions. The solid lines of the bolt in Figure 4 represent the latched position, and 50 the broken lines indicate the unlatched position.

It will be noted that the bolt has two projections 24 and 25 spaced from each other angularly about the axis of the pin 22. The bolt projections extend rearwardly through the slot 20 in the rear edge of the door and coat with a keeper 26 which is secured to the body pillar 15 in registration with the bolt 21. The keeper 26 has a locking face 27 at the end facing the inner side of the door and has an abutment face 28 at the end facing the outer side of the door. The distance between the locking face 27 and the abutment face 28 is predetermined with respect to the distance between the angularly spaced projections 24 and 25 on the bolt 21 in order to operate the bolt.

The bolt 21 is normally urged to its unlatched position shown by the broken lines in Figure 4, and this is accomplished by a spring 29 wound around the pin 22 at one side of the bolt. One end of the spring 29 engages the outer edge of the bolt, and the other end of the spring abuts the adjacent part of the bracket 17. Assuming that the bolt 21 is in its unlatched position, and that the door 10 is moved toward its closed position, it will be noted that the free end of the projection 25 on the bolt abuts the face 28 on the keeper 26. As a result continued closing movement of the door rotates the bolt in a counterclockwise direction (Figure 4) and moves the projection 24 into locking engagement with the face 27 on the keeper 26.

The above latched position of the bolt 21 is indicated by the solid lines in Figure 4, and the bolt is held in this position by a block 30 supported in the channel 19 of the bracket 17 at the outer side of the bolt 21. The block 30 is slidable in the channel 19 in directions toward and away from the bolt 21, and is yieldably urged toward the bolt 21 by a coil spring 31. The coil spring 31 is positioned in the channel 19 at the outer side of the block 30 in a manner such that the opposite ends thereof respectively engage the block 30 and a part 32 of the bracket 17. The coil spring is held in place by a pin 33 secured to the block 30 and extending axially through the coil spring 31. The part 32 is apertured to provide clearance for the outer end of the pin 33 during sliding movement of the block 30.

The block 30 is held in position by a pin 34 extending transversely of the channel 19 and projecting through a slot 35 in the block 30. The slot 35 is elongated in the direction of sliding movement of the block so as not to interfere with the operation of the block.

Referring again to Figure 4, it will be seen that when the bolt 21 is in its latched position, the projection 25 on the bolt extends into the channel 19 and the outer surface of the projection 25 is positioned for engagement by the inner end of the block 30. The outer surface of the projection 25 is fashioned with a plurality of serrations 36, and the inner end of the block 30 is formed with corresponding serrations 37. The serrations 36 and 37 are arranged to successively mesh with one another as the bolt 21 is rotated to its latched position. The serrations are held in intermeshing relationship by the spring 31 and movement of the bolt 21 to its unlatched position is accordingly prevented until the block 37 is retracted from the bolt against the action of the spring 31. It may be pointed out at this time that the bolt is effectively held by the block as soon as the first serrations intermesh so that in effect a safety catch is provided.

The block 30 may be released from the bolt 21 by manipulating either the inside or outside con-

trols 38 and 39 respectively. As shown particularly in Figures 2 and 4 of the drawings, a slide 40 is mounted on the bracket 17 at the base of the channel 19 for sliding movement in opposite directions between the inner and outer door panels.

The slide 40 is held in assembled relationship to the bracket by a strap 41 suitably secured to the bracket 17. The outer end of the slide 40 is formed with a slot 42, and the adjacent portion of the base of the channel 19 has a registering slot 43. A pin 44 is anchored to the block 30 and projects through the registering slots 42 and 43 for engagement by a projection 45 formed on the slide 40 at the inner side of the pin 44. The arrangement is such that outward sliding movement of the slide 40 engages the projection 45 with the pin 44 and moves the block 30 out of locking engagement with the projection 25 on the bolt 21.

The inside control 38 is connected to the slide by an inverted U-shaped rod 46 having the base portion pivotally mounted on the inner door panel 12 in the manner indicated by the reference numeral 47 in Figure 5 of the drawings. One leg 48 of the rod is positioned at the inner side of a flange 49 which projects laterally from the inner end of the slide 40 so that rocking movement of the rod 46 in a direction outwardly of the door engages the leg 48 with the flange 49 and moves the slide 40 outwardly to in turn move the block 30 out of engagement with the bolt 21. As shown in Figure 4 of the drawings, the flange 49 on the slide 40 is yieldably urged into engagement with the leg 48 by the spring 31 acting on the block 30.

The leg 50 of the rod 46 is shown in Figure 6 of the drawings as bent laterally inwardly to project through an opening 51 formed in the trim panel 52 at the inner side of the door. The inwardly bent portion of the leg 50 provides a mounting for the control 38 which is in the form of a push button. A suitable guard ring 53 is secured to the inner side of the trim panel 52 and surrounds the control 38 to protect the latter against accidental movement.

It follows from the above that movement of the control 38 in the direction of opening movement of the door 10 rotates the bar 46 in a direction to move the leg 48 in an outward direction relative to the door. Since the leg 48 is engaged by the slide 40, the latter is moved outwardly relative to the bracket 17. As pointed out above the slide 40 is connected to the block 30 through the medium of the pin 44 and outward movement of the slide 40 imparts a corresponding sliding movement to the block 30. Outward movement of the block 30 a distance greater than the depth of the serrations 36, 37 releases the bolt 21 and permits the spring 29 to rotate the bolt to its unlatched position.

It has been stated above that the bolt 21 is also released by manipulation of the control 39 at the outer side of the door. As shown particularly in Figure 2 of the drawings, a lever 55 has the lower end thereof pivoted by a pin 56 to the bracket 17 at a point below the slide 40. The lever 55 is bent to extend over the slide 40, and to engage the inner side of the projection 45 on the slide 40. The upper end of the lever 55 is pivoted to the inner end of an arm 57, and the outer end of the arm projects through a slot 58 in the outer panel 11 of the door for connection to the control 39.

The control 39 has a base part 59 and a handle part 60. The base part is secured to the outer

panel 11 of the door, and has a slot 61 in registration with the slot 58 for receiving the outer end of the arm 57. In addition the base 59 has an annular outwardly extending bearing flange 62, and has laterally spaced outwardly extending flanges 63 extending generally diametrically across the same.

The handle part 60 has a central portion 64 shaped for convenient engagement by one hand of the operator and has an annular portion 65 arranged in bearing contact with the annular portion 62 of the base 59. The annular portion 65 has a diametrically extending rib 66 shown in Figure 3 of the drawings as integrally connected to the portion 64 by laterally spaced flanges 67. The flanges 67 are spaced laterally from opposite sides 68 of the portion 64, and the resulting spaces slidably receive the flanges 63 on the base 59. Attention is called to the fact that the outer edges of the flanges 63 are arcuate, or in other words, are formed on a radius. The arrangement is such that the handle part 60 may be tilted in an outward and downward direction relative to the base 59. This action enables manipulation of the control 39 with a minimum amount of effort on the part of the operator.

In order to transmit movement of the handle part 60 to the arm 57 the outer end of the arm has a T-shaped section 70 providing opposed slots 71. The rib 66 has an elongated slot 72 which extends in a direction normal to the head portion of the T-shaped end of the arm 57, and this slot is of sufficient length to freely receive the T-shaped head during assembly. It will be understood that during assembly, the part 60 of the control is rotated to a position wherein the T-shaped head may be projected through the slot 72. Upon completion of this operation the part 60 is rotated 90° in order to locate the T-shaped head 70 crosswise of the slot 72 as shown in Figure 2 of the drawings. The part 60 is then moved inwardly relative to the base part 59 and the annular portion 65 on the part 60 is seated on the bearing flange 62 on the base part 59. The handle part 60 and base part 59 are held in assembled relationship by a coil spring 72 surrounding the arm 57. The outer end of the coil spring abuts the inner side of the outer door panel 11 and the inner end of the coil spring engages a suitable stop 73 on the arm 57.

The above construction is such that outward movement of the handle part 60 on the control 39 displaces the arm 57 in a corresponding direction against the action of the spring 72. Outward movement of the arm 57 engages the lever 55 with the projection 45 on the slide 40 and moves the latter outwardly. Movement of the slide 40 in an outward direction imparts a corresponding movement to the block 30 through the pin 44, and disengages the block from the rotary bolt 21.

In accordance with this invention provision is made for blocking movement of the slide 40 to its bolt releasing position, and this action may be accomplished from either side of the door. As shown in Figures 2 and 5 of the drawings, a vertical rod 75 is slidably supported as at 76 on the bracket 17. The upper end of the rod extends through an opening in the window ledge of the door, and has a control knob 77 thereon. A portion 78 of the rod below the bracket mounting 76 is offset laterally outwardly for a limited distance, and this offset portion provides a shoulder 79 on the rod which assumes a position in advance of the flange 49 on the slide when the rod 75 is depressed to its lowermost position.

Thus movement of the slide 40 by either the inside control 38 or the outside control 39 to release the bolt 21 is prevented by the rod 75 when the latter is moved to its lowermost position.

Referring again to Figure 2 of the drawings it will be noted that the lower end 80 of the rod portion 78 is offset laterally outwardly and is secured to the swinging end of a lever 81. The lever 81 is secured to a shaft 82 which extends transversely of the door, and is rotatably supported at the inner end in a part 83 of the bracket 17. The outer end of the shaft 82 is connected to a key operated cylinder 84 mounted on the outer door panel 11 in the usual manner. As shown in Figure 7 of the drawings, the cylinder 84 has axially extending projections 85 positioned for alternative engagement with a pin 86 projecting laterally from the shaft 82. The arrangement is such that when the cylinder 84 is rotated by the key in a counterclockwise direction, the pin 86 is engaged by one of the projections 85 to rotate the shaft 82 in a corresponding direction until the pin 86 engages a stop 87 on the cylinder casing 88. On the other hand when the cylinder 84 is rotated in a clockwise direction, the other projection 85 engages the pin 86 and rotates the shaft 82 throughout an angular distance of travel determined by a second stop 89 on the cylinder casing 88.

When the shaft 82 is rotated in a clockwise direction, the rod 75 is moved downwardly by the lever 81 to position the part 78 of the rod in blocking relationship to the slide 40. On the other hand when the shaft 82 is rotated in a counterclockwise direction, the rod 75 is raised by the lever 81 to locate the blocking part 78 of the rod above the path of travel of the bolt releasing slide 40 so as not to interfere with the action of this slide.

From the foregoing it will be understood that the inside control 38 and outside control 39 are moved in the general direction of opening movement of the door in order to release the latch bolt 21. Thus the effort required to effect release of the latch bolt 21 is reduced to a minimum, and the inside control may be located substantially flush with the trim panel of the door. As a result the inside latch control 38 is out of the way and does not interfere with the occupants of the vehicle body.

As shown in Figure 10 of the drawings the keeper 26 has top and bottom flanges 85' at opposite sides of the bolt engaging part of the keeper. These flanges coat with the bolt 21 in the latched position of the latter to provide an effective dovetail.

What I claim as my invention is:

- Door latch mechanism comprising a support plate formed of sheet metal bent to provide a longitudinally extending channel having side and bottom walls, an end closure for said channel having a hole therein, said plate being secured to the inner surface of an edge flange of a door, said flange having an opening therethrough in registry with said channel, a pivot pin spanning the side walls of said channel, a rotary latch bolt in said channel rotatably mounted on said pin and having portions extending through said opening, a block in said channel between said end closure and said bolt, a pin extending from said block and passing through the hole in said end closure, a spring surrounding said pin, interlocking serrations on said block and said bolt, the bottom wall of said channel having a slot therein, and an actuating pin on said block extending

through said slot for actuation by manually operated latch release means.

2. Door latch mechanism as defined in claim 1 in which said block is provided with a transverse opening elongated in the direction of the channel, and a pin is provided in said opening extending therethrough and having its ends carried by the opposite side walls of the channel, said pin and elongated opening being located to retain the serrated face of the block in position to be engaged by the serrations on said block when the door is swung to closed position.

3. In latch mechanism of the class described, a mounting plate formed to provide an elongated channel having side and bottom walls, an end wall closing one end of said channel, a latch bolt in the form of a lever having angularly disposed latching and actuating arms, pivot means extending between the sides of said channel mounting said latch bolt for pivotal movement, a block slideable in said channel, a pin and elongated slot connection between said block and channel side walls, the end wall of said channel having a hole therein, a pin extending from said block through said hole, a compression spring surrounding said pin and bearing against said block to urge it toward said pivot means, one of said channel bottom and side walls having an elongated slot, a latch release pin on said block extending through said slot, and interlocking surfaces on the end of the actuating arm of said bolt and the end of said block adjacent said bolt

to lock said arm in latching position when engaged by said block.

4. Latch mechanism as defined in claim 3 comprising a latch release member, means mounting said member for sliding movement on the outer surface of the bottom wall of said channel, and an abutment on said member engageable with said latch release pin for moving it to move said block in latch release direction against said spring.

5. Latch mechanism as defined in claim 3, said plate having ears for mounting it on the inside surface of the edge closure of a hollow support with the open side of its channel in registration with a slot in the edge closure.
